UNITED STATES PATENT OFFICE

ELLSWORTH W. CARROLL, OF SAN FRANCISCO, CALIFORNIA

DESIGN FOR AN AUTOPLANE

Application filed April 7, 1931. Serial No. 39,389. Term of patent 14 years.

To all whom it may concern:

Be it known that I, ELLSWORTH W. CARROLL, a citizen of the United States of America, residing at San Francisco, in the county of San Francisco and State of California, have invented a new, original, and ornamental Design for Auto-Plane, of which the following is a specification, reference being had to the accompanying drawing, forming part thereof.

In the drawing;

Figure 1 is the side elevation of my new

auto-plane in the position which it assumes when at rest,

Figure 2 is a fragmentary plan of the auto-plane illustrated in Figure 1, and

Figure 3 is a front elevation of the auto-plane illustrated in Figure 1 showing its landing gear and the landing gear concealing means extended.

I claim:

The ornamental design for an auto-plane, as shown.

ELLSWORTH W. CARROLL.
